UNITED STATES PATENT OFFICE.

JOHN CRISTIAN KORN, OF WILKES-BARRE, PENNSYLVANIA.

COMBINATION SLED AND WHEELED VEHICLE.

Application filed July 9, 1926. Serial No. 121,419.

This invention aims to provide novel means for so equipping a sled that it can be used either upon ice or snow, upon the one hand, or upon bare ground upon the other hand.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the drawings:—

Figure 1 shows in side elevation, a sled equipped with the device forming the subject matter of this application;

Figure 2 is an end elevation of the sled;

Figure 3 is a perspective showing the arm;

Figure 4 is a perspective showing the standard.

The numeral 1 marks a sled including a body made up of a platform 2 joined by knees 3 to the upstanding flanges 4 of runners 5, the runners, in the present embodiment of the invention, but not necessarily, being in the form of T members.

In carrying out the invention there is provided any desired number of standards 6 supplied at their upper ends with rectangularly disposed head plates 7 having openings 8. The standard 6 has a broadened foot 9 supplied with a seat or notch 10, the foot 9, thus, being bifurcated. The foot 9 is equipped with a transverse opening 11. Intermediate its ends, the standard 6 is supplied with a hub 12 which is wider and thicker than the standard, the hub being supplied with a plurality of ribs 14 disposed radially with respect to a central opening 15 in the hub.

The numeral 16 marks an arm equipped at its upper end with a hub 17 having a central opening 18, the hub being supplied with a laterally projecting rim 19 having

notches or seats 20. At its lower end, the arm 16 carries an outwardly extended and downwardly prolonged lateral bracket 21 of rectangular form, the bracket being sustained from the arm 16 through the instrumentality of a brace fin 22. A shaft 23, which may be a bolt, is mounted in the lower end of the bracket 21 and in the lower end of the arm 16. A wheel 24 is journaled for rotation on the shaft 23 and is located within the bracket 21.

The upstanding flange 4 of the runner 5 is received in the notch 10 that is formed in the lower end of the standard 6. The head plate 7 abuts against the under surface of the platform 2. A securing element 25 passes through the opening 11 in the standard 6 and through the flange 4 of the runner 5. Securing elements 26 are mounted in the openings 8 of the foot plate 7 and connects the foot plate to the platform 2. Generally stated, the standards 6 are mounted at their upper ends on the body of the sled 1 and are mounted at their lower ends on the runners 5. The hub 17 of the arm 16 is placed against the hub 12 of the standard 6, with the ribs 14 of the hub 12 engaged in the notches 20 which are formed in the rim 19 of the hub 17. A clamping device 27, such as a bolt and wing nut, is mounted in the openings 18, and, thus, the arm 16 may be held at any desired angle with respect to the standard 6, the ribs 14 and the notches 20 constituting interlocking elements, which, in conjunction with the clamping bolts 27 will retain the arm 16 at any desired angle with respect to the standard 6.

If desired, the arm 16 may be held in the approximately horizontal position shown at 28 in Figure 1. Then, the runners 5 of the sled come into play, in the usual way. If sufficient snow to operate the sled as such is lacking, then the arms 16 may be swung down into the vertical position shown in dotted line in Figure 1, the sled 1 being elevated a maximum amount. This operation is followed when the surface of the ground, roadway or side walk is somewhat rough. If the surface over which the vehicle is travelling, is reasonably smooth, then the arms 16 may be held at an acute angle to the standards 6, as shown at 29 in Figure 1, the sled 1 being raised far enough so that it can run on the

wheels 24, the runners 5, at the same time, being disposed close to the ground.

What is claimed is:—

In a device of the class described, a standard, an arm, a wheel journaled on the arm, the standard and the arm being provided with hubs, radial tongue and groove ele-

ments on the hub, and a clamping device connecting the hubs and holding the tongue and groove elements interengaged.

In testimony that I claim the foregoing as my own, I have hereto affixed my signature.

JOHN CRISTIAN KORN.
